US00D965740S

(12) **United States Design Patent** (10) Patent No.: **US D965,740 S**
(45) Date of Patent: **** Oct. 4, 2022**

(54) **GAS SUPPLY NOZZLE FOR SUBSTRATE PROCESSING APPARATUS**

D773,609 S * 12/2016 Morita D23/213
D783,351 S * 4/2017 Fujino D7/407
D828,091 S * 9/2018 Fujino D7/407

(57) **CLAIM**

(51) **LOC (13) Cl.** **23-01**

The ornamental design for a gas supply nozzle for substrate processing apparatus, as shown and described.

(52) **U.S. Cl.**

USPC **D23/213**

DESCRIPTION

(58) **Field of Classification Search**

USPC D23/213, 214, 215, 223, 224, 226, 229, D23/230; D7/407

CPC A61H 9/0021; A61H 33/00; B05B 1/00; B05B 1/14; B05B 1/185; B05B 1/08; B05B 1/02; B05B 1/26; B05B 12/002; B05B 1/18; B05B 9/01

See application file for complete search history.
